Primary Examiner — R. Johnson(74) *Attorney, Agent, or Firm* — Robert D. Atkins; Patent Law Group(57) **CLAIM**

The ornamental design for a guitar body, as shown and described.

DESCRIPTION

FIG. 1 is a perspective view of a guitar body showing our new design.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom plan view thereof.

FIG. 8 is a front view thereof, showing the guitar body in use; and,

FIG. 9 is a perspective view thereof.

The portions of the guitar body shown in broken lines represent environmental structure and form no part of the claim.
